UNITED STATES PATENT OFFICE.

WILLIAM F. WAGNER, OF SAN DIEGO, CALIFORNIA, ASSIGNOR OF THIRTY-FIVE PER CENT TO ARTHUR W. PEARSONS, OF SAN DIEGO, CALIFORNIA.

TIMER.

Application filed August 4, 1921. Serial No. 489,841.

To all whom it may concern:

Be it known that I, WILLIAM F. WAGNER, a citizen of the United States, residing at San Diego, in the county of San Diego and 5 State of California, have invented certain new and useful Improvements in Timers; and I do declare the following to be a full, clear, and exact description of the invention, such as will enable others skilled in 10 the art to which it appertains to make and use the same.

This invention relates to an improved timer for use in connection with an internal combustion engine and one object of the invention is to provide an improved type of movable contact carrier including a bell crank lever pivotally and slidably mounted and having one of its arms provided with an abutment for engagement by abutments carried 20 by a collar mounted upon a driving shaft, the bell crank lever being rocked upon its pivot when the shaft is rotated in one direction to bring the movable contact carried by the lever into engagement with a stationary contact and the lever having sliding movement when the shaft rotates in a reverse direction thus preventing the movable contact from engaging the stationary contact.

Another object of the invention is to 30 provide an improved type of spring carrier strip for one of the contact points, the strip permitting the contacts to move into tight engagement and the strip bending after contacting thus permitting close contact but at the same time preventing danger of breakage.

Another object of the invention is to 40 provide a timer in which the movable contacts may have sliding engagement with the stationary contacts thus providing a wiping action which will serve to keep the contacting faces of the contact points clean and well polished.

Another object of the invention is to 45 provide a timer which will be simple in construction, efficient in operation and not liable to readily get out of order.

This invention is illustrated in the accompanying drawings, wherein:

50 Figure 1 is a view showing the improved timer in vertical section.

Figure 2 is a top plan view of the timer base with the contacts out of engagement.

55 Figure 3 is a similar view showing the contacts in engagement.

Figures 4, 5 and 6 are sections taken along the lines 4—4, 5—5 and 6—6 respectively of Fig. 2.

Figures 7 and 8 are views similar to Figs. 4 and 5 taken through a timer having a 60 slightly modified construction.

Figure 9 is a sectional view taken along the line 9—9 of Fig. 7.

Figure 10 is a view similar to Fig. 6 taken along the line 10—10 of Fig. 7. 65

The timer is provided with a base 1 having a depending neck 2 in which is rotatably mounted a shaft 3 adapted for connection with a shaft 4 which will be rotated from the drive shaft of an internal combustion 70 motor. It will thus be seen that the shaft 3 will be rotated in timed relation to the rotation of the crank shaft of the motor. A collar 5 is secured upon the inner end portion of the shaft 3 by means of a sc 75 curing bolt 6 which has its head extended for fitting into a recess formed in a head or crown 7 which fits upon the upper end portion of the collar 5. This head or crown 7 carries a distributor arm 8 one end of 80 which engages a terminal 9 for a conductor 10 leading from a coil. The second end portion of this distributor arm is adapted to engage the terminals 11 of the conductors 12 which lead to the plugs and it will thus 85 be seen that the plugs will be energized in proper order. The cover 13 which carries the terminals 9 and 11 fits upon the base and is releasably held in place by the catches 14 carried by the base as shown in Fig. 1. 90

A lever 15 which is substantially L-shaped and therefore resembles a bell-crank lever rests upon the base 1 and is slidably and pivotally held in place by a screw 16 which passes through a slot 17 formed in the lever 95 15. This lever has its arms provided with upstanding end portions or heads 18 and 19 and the head 18 carries an abutment block 20 which extends toward the collar 5 so that as the shaft 3 rotates, the abutment lugs 21 of the collar 5 will engage this block and impart movement to the lever. It should be noted that the block is cut to provide a shoulder 22 and that the teeth 21 are so cut that when the shaft 3 is rotating in 100 the direction indicated by the arrow, the teeth or lugs 21 will engage block 20 and rock the lever upon its pivot 16 whereas if the shaft should rotate in an opposite direction as would occur when a motor back-fires, 110

the lugs or teeth 21 would engage the abutment and the lever would slide instead of swinging. When the lever swings upon its pivot, contacts will be brought into engagement as will be hereinafter brought out but when the engine tries to back-fire and the shaft is rotated in the reverse direction, the lever will slide instead of swinging upon its pivot and no contact will be formed and therefore continued rotation of the shaft 3 due to back-firing of the motor will be prevented. The head 19 is positioned substantially parallel to the head 18 and is positioned upon the opposite side of the collar and shaft from the head 18. It will thus be seen that when the lever 15 rocks upon its pivot, the head 19 will swing relatively toward the shaft 3 and will to a certain extent have movement radially of the shaft. A rigid strip 23 extends parallel to the head 19 and carries a pin 24 which extends through an enlarged opening formed in a resilient strip 25, one end portion of which is bent to engage the inner face of the rigid strip 23. Registering openings are formed in these strips to receive insulating sleeves 26, which in addition to passing through the strips 23 and 25 also pass through openings formed in an insulating strip 27 positioned between the strip 25 and the head 19. It will thus be seen that when the screws 28 are tightened, the strips 23 and 25 will be securely held in place and will be insulated from the lever 15. A pin 29 extends outwardly from the rigid strip 23 and is engaged by a spring 30 so that the lever will be yieldably held in a normal position as shown in Fig. 2 with the contact points 31 of this movable contact element out of engagement with contact screws 32 which pass through the threaded openings formed in the shoulder 33 of the bracket 34. This shoulder is split as shown in Fig. 4 and a securing screw 35 is provided so that the portions of the shoulder may be drawn into binding engagement with the contact screws 32 and secure the screws in a set position. It is desired to limit movement of the relatively movable contact away from the stationary contact and therefore there has been provided at post 36 which is eccentrically mounted by means of a pin 37 and provided with a disk-like base 38. The post is rotatable upon the stem 37 and the base is provided with a slot 39 through which passes a screw 40. By rotating the post, the amount of movement permitted when the movable contact is moving away from a stationary contact can be controlled. It will thus be seen that when the contacts are separated as shown in Fig. 2, passage of current from the wire 41 through the conductor 42 to the strip 23 and from the strip 23 to the bracket 34 and back to the wire 43 will be interrupted, whereas when the contacts 31 and 32 are in engagement, free passage will be permitted. It will be further noted that when the block 20 is engaged by one of the lugs 21 and swung upon its pivot, the contact points 31 will first engage the ends of the screws or contacts 32 and will then slide across the end of these screws thus providing a rubbing contact which will clean the contacting faces of the screws and contact points 31. If the motor should back-fire, contact will be prevented and continued back-firing will not occur due to the fact that instead of swinging upon its pivot, the lever will be moved longitudinally of the slot 17 and the contacts will not be brought into engagement. As previously stated, the provisions of the resilient strip 25 permits the contacts to come in close engagement thus preventing breaking and also preventing extra wear upon the contact points 31 and end of the screw 32.

In the preferred form, the strip 25 is provided with a plurality of contact points 31 and a plurality of contact screws 32 are carried by the bracket 34. By providing a plurality of contacts 31 and 32 a good contact is assured and further rapid consumption of the contact points is prevented. If, however, it is desired to provide a cheaper distributor, a single contact 31 and a single screw 32 may be provided as shown in Figs. 7 through 10.

I claim:

1. A timer comprising a base, a rotatable shaft extending through the base, a stationary contact carried by the base, a lever pivotally carried by the base and having arms, extending in diverging relation from the point of mounting, a rigid strip carried by one arm of the lever and having movement toward and away from the stationary contact when the lever moves pivotally, a resilient strip carried by one end of said rigid strip and having its free end provided with a longitudinally extending cutout, a pin carried by said rigid strip and extending through the cutout and having a head engaging the resilient strip to limit movement thereof away from the rigid strip, a contact point carried by the free end portion of said resilient strip for engaging the stationary contact when said lever is moved to swing said rigid strip towards said stationary contact, and actuating means for imparting swinging movement to the lever when the shaft rotates in one direction and moving the rigid strip towards said stationary contact to bring the contact point of said resilient strip into contact with the stationary contact, the cutout in said resilient strip permitting longitudinal movement thereof to cause rubbing of the contact carried thereby against the stationary contact.
2. A timer comprising a base, a rotatable shaft extending through the base, a station-

ary contact carried by the base, a lever pivotally and slidably mounted upon the base at a point diametrically opposite the rotatable shaft from the stationary contact and having 5 diverging arms, one arm extending toward the stationary contact and carrying an abutment element extending toward the shaft, a contact carried by the second arm of the lever and extending parallel to the first arm 10 upon the opposite side of said shaft, resilient means yieldably holding the lever against movement, and means carried by said shaft for engaging the abutment element of the lever as the shaft rotates, rotation of the 15 shaft in one direction imparting swinging movement to the lever to bring the movable contact into rubbing contact with the stationary contact and reverse rotation of the

shaft imparting sliding movement to the lever with the contacts out of engagement. 20

3. A timer comprising a base, a stationary contact carried by said base and a movable contact carried by said base and movable toward and away from the stationary contact, an eccentrically mounted abutment post 25 limiting movement of the movable contact away from the stationary contact, means yieldably holding the post in an adjusted position, resilient means yieldably holding the movable contact in engagement with the post, and means for moving the movable contact into engagement with the stationary contact. 30

In testimony whereof I have hereunto set my hand.

WILLIAM F. WAGNER.
